UNITED STATES PATENT OFFICE.

DANIEL R. ALLEN, OF NORTH AUGUSTA, SOUTH CAROLINA.

ELECTRICALLY-OPERATED SWITCH.

1,195,892.

Specification of Letters Patent. Patented Aug. 22, 1916.

Application filed August 7, 1914. Serial No. 255,677.

To all whom it may concern:

Be it known that I, DANIEL R. ALLEN, citizen of the United States, residing at North Augusta, in the county of Aiken and State of South Carolina, have invented certain new and useful Improvements in Electrically-Operated Switches, of which the following is a specification.

My invention relates to new and useful improvements in railway switches of the type employed between a main line track and branch line track to permit trains to pass in either direction along the main line track, from the main line track onto the branch line track or from the branch line track onto the main line track.

The primary object of my invention consists in the provision of a simple form of switch structure by which practically all possibility of derailment will be prevented as the rails, switch points and frogs are so constructed as to, at all times, afford a relatively smooth and continuous support either for the wheel treads or their flanges.

A further object of my invention is to construct a switch of the above described character having but a single moving switch point, the remaining switch point being fixed.

With these and other objects in view, my invention will be more fully described, illustrated in the accompanying drawings, and then specifically pointed out in the claims which are attached to and form a part of this application.

In the drawings: Figure 1 is a fragmentary top plan view of my improved switch structure, together with the electrical mechanism for operating it; Fig. 2 is a transverse sectional view taken on the line 2—2 of Fig. 1, looking in the direction of the arrows; Fig. 3 is an enlarged top plan view of the free end of the stationary switch point, together with the adjacent track rail, a car wheel being shown about to pass onto the switch point; Fig. 4 is a perspective view of the structure shown in Fig. 3, together with a fragment of the third rail; Fig. 5 is a perspective view of a curved rail section which forms a portion of the track adjacent the fixed switch point; Figs. 6^a and 6^b are transverse sectional views taken on corresponding section lines of Fig. 5, looking in the direction of the arrow; Fig. 7 is a transverse sectional view, upon an enlarged scale,

of the rails at one side of the frog, this view being taken on the line 7—7 of Fig. 1, looking in the direction of the arrow; Figs. 8 and 9 are similar views, taken on corresponding section lines of Fig. 1, also looking in the direction of the arrows; Fig. 10 is a fragmentary perspective view illustrating the connection between the switch operating mechanisms and movable switch point.

Corresponding and like parts are referred to in the following description and indicated in all the views of the drawings by the same reference characters.

In disclosing my improved switch structure I have illustrated it in connection with a main track 10 and branch track 11, each including track rails 12 and 13 of the usual type secured to and supported upon cross ties 14 of any desired form or material. As will be seen by reference to Fig. 1, the rails 12 constitute the outer rails of the track, while the rails 13 constitute the inner rails, these latter rails leading to a frog 15 from which extend the movable switch point 16 and stationary switch point 17, the former, at its free end, co-acting with the outer rail 12 of the main track, while the latter contacts with the juncture of the outer rail 12 of the branch track and the inner rail 13 of the main track, in effect, forming a continuation of the rail 13. Frog guards 18 and 19 lead from the switch points 16 and 17 to the frog 15 and guard rails 20 and 21 are located adjacent the switch points 16 and 17 in the usual manner. A guard rail 22 extends along the outer rail 12 of the main track at the other side of the switch point 16, while a guard rail 23 extends along the outer rail 12 of the branch track, from a point immediately adjacent the switch point 17, the free ends of all of these guard rails, as well as the frog guards, being bent from their respective rails in the usual manner.

The free end or point proper of the fixed switch point 17, is spaced slightly from the inner face of the adjacent rail 13, as shown at 24, and has its inner face rounded to provide a cam face 25 for engagement by the flanges of the car wheels when the train is to pass along the main line track, in the direction of the arrow. The space 24 between the switch point and rail 13 is slightly greater in width than the width of the flange in order that, under certain other

conditions, that is, when a train going in the same direction is to branch off onto the side track, the car wheel flanges may pass between the switch point and rail 13, the 5 wheels remaining on the rail 13. The switch point 16 is mounted for swinging movement in such a manner that its free end or point proper may be moved either into engagement with the outer face of the guard 10 rail 20 or the inner face of the main track rail 12, the inner face of such switch point being beveled slightly and its outer face being cut-away at a long angle in order that the car wheels may pass smoothly from the 15 rail 12 to the switch point 16, when the switch point is in the latter position.

One of the primary objects of my invention is to so construct certain of the various rails above described that the car wheels 20 will be automatically maintained upon the proper rails, depending upon the direction of the train and the track which it is passing over and further in such a manner that jumping or dropping of the wheels in passing 25 the various switch points or in passing through the frog will be reduced. In accomplishing this, I construct the rail or rails which form that portion of the track, best indicated at *a* in the manner best illustrated 30 in Figs. 5, 6^a and 6^b. In these figures, that portion of the track is illustrated as consisting of a single curved rail but in practice it will usually be made up of a number of rail lengths in order to give sufficient 35 length to the curve. However, these separate rails, when properly laid in alinement with each other, will appear and operate the same as though they were one and for this reason they may well be illustrated as, 40 in effect, constituting a single rail. Referring to the above figures, it will be seen that the inner portion of this rail is thickened in a manner which may best be described by stating that the inner rail flange is thickened 45 in such a manner that its upper face *b* extends at an angle of 20 degrees to the horizontal. It should further be noticed, however, that the extent to which the flange is thickened varies at different portions of 50 the rail, the flange being thickest at a point directly opposite the terminal of the switch point 17, at which point its upper edge joins with the lower edge of the rail head, its lower edge being located considerably to 55 one side of the flange portion proper of the rail. From this point, this thickened flange portion decreases in height uniformly and gradually in both directions, gradually merging to a rail flange of ordinary thickness. In like manner, the inner flanges of 60 the rail sections 13 leading to the frog 15 are thickened, as also are the inner flanges of the switch points 16 and 17, the thickening of these latter flanges being clearly illustrated at *c* and *d*, respectively, in Figs. 7 to

9 of the drawings, the place of greatest thickness for all of these latter rail sections being directly at the frog.

Assuming that a train is passing along the main track in a direction contrary to 70 that indicated by the arrow, the outer wheels will pass along the outer track 12 and the inner wheels along the inner track 13, the flanges of the inner wheels engaging the inclined faces of the inner thickened flanges 75 of the rail section 13 leading to the frog and the switch point 17 leading from the frog in such a manner as to force the outer wheels of the car toward the outer rail until their flanges engage snugly against the inner face of the head of such rail. Under these circumstances, although the inner wheels have not, in effect, been raised or lowered, the car trucks, as a whole, have been shifted somewhat bodily toward the 80 outer portion of the track and the inner wheels are largely supported by their flanges upon the thickened rail flanges which form a continuous uninterrupted bearing surface through the frog, thus avoiding either 85 jumping or dropping of the wheels as is often the case with frogs and frog rails as now constructed. Upon the passage of the car past the switch points, the inner wheels engage the inclined face *b* of the rail section 90 *a* and because of this engagement there is practically no jar or lost movement upon passage of the wheels from the switch point 17 to the main track rail 13. At the same time, the various guard rails, above described, prevent derailment of the cars. If the train is passing from the branch track onto the main track, the effect will be substantially the same, the car trucks, while 95 passing the frog 15, being forced toward 100 the rail 12 of the branch track and when passing through the switch proper being held against the rail 12 of the main track.

A train approaching the switch in the direction of the arrow, assuming that the 110 switch is closed, as shown in Fig. 1, will of course pass along the main track. This is absolutely insured, in spite of the fact that the switch point 17 is stationary, because of the inclined face *b* of the thickened 115 inner flange of the rail section *a* which engages the flanges of the wheels passing upon the rail section *a* to force the car trucks toward the outer rail 12 in such a manner that the inner wheels of the trucks will readily 120 pass onto the switch point 17, the flanges of the inner wheels being spaced from the tread of the rail which they are traveling on, because of this engagement, as shown in Fig. 2 and also illustrated in Fig. 3. As the passage of the car past the frog is identical 125 with the passages previously described, this need not be again traced out. Assuming that the car is to pass along the branch track from the main track, the movable 130

switch point 16 is swung to bring its free end in engagement with the outer rail 12 of the main track. Under these conditions, the outer wheels of the car trucks engage 5 this switch point before they come to the free end of the switch point 17 and are forced by it toward the rail section *a* in such a manner that the flanges of the inner wheels of the trucks will pass freely through 10 the space 24 between the rail section *a* and switch point 17.

As previously pointed out, a still further object of my invention is the provision of train controlled automatic means for throwing the switch, when desired. In this connection, I provide a support 30 located adjacent the outer side of the main track near the free end of the switch point 16 and upon this support I mount a solenoid having a 15 reciprocating plunger which is pivotally connected at its outer end to a link 34 which extends between adjacent ties of the track, terminating in an upwardly directed hook or finger 35 which engages about the inner 20 flange of the switch point 16, the body of the link extending beneath the rail 12 and switch point. It will therefore be seen that upon energization of this solenoid, the movement of its plunger will act through the 25 link 34 to swing the switch point into engagement with the main rail 12 of the track. Under normal circumstances, the switch point is held in opposite position by a spring 30 operatively connected to the switch point, 35 as shown at 37 and to one of the ties as shown at 38. Although I have illustrated a helical torsion spring in the drawings, it will of course be understood that a compression spring may be employed or in fact 40 any suitable type of spring which may be adapted for the purpose desired.

In connection with the above described switch actuating mechanism, I preferably provide a switch operating link 74 connected 45 to the switch point 16 in the same manner as the link 34, but connected at its opposite end to the crank arm 75 of a hand switch stand 76 having the usual hand lever 77. It will be clear that with this arrangement, 50 the switch may be closed either by energizing the solenoid or by proper manipulation of the hand lever 77, either actuating means assuming the switch stand to be unlocked, being entirely independent of the other.

55 It will of course be understood that I do not wish to limit myself to the specific details illustrated and described as various changes, within the scope of the appended claims, may be made at any time, without

in the slightest degree departing from the 60 spirit of my invention.

Having thus described the invention, what is claimed as new is:

1. In a switch construction, the combination with a fixed switch point and a swinging switch point, of track rails co-acting with such switch points, that track rail adjacent the fixed switch point being spaced from such point and having its inner flange thickened to provide a cam wheel engaging 65 face.

2. In a switch construction, the combination with a fixed switch point and a swinging switch point, of track rails co-acting with such switch points, that track rail adjacent the fixed switch point being spaced from such point and having its inner flange thickened to provide a cam wheel engaging 75 face, said cam face being inclined at an angle of substantially twenty degrees to 80 the horizontal.

3. In a switch construction, the combination with a fixed switch point and a swinging switch point, of track rails co-acting with such switch points, that track rail adjacent the fixed switch point being spaced from such point and having its inner flange thickened to provide a cam wheel engaging 85 face, said cam face being inclined at an angle of substantially twenty degrees to 90 the horizontal, the thickening of such rail being greatest adjacent the free end of the switch point and gradually diminishing in both directions from such point.

4. A rail section for switches and frogs 95 including a body portion having a base flange, web and head, the web being thickened to provide cam wheel engaging faces forming continuations of each other, said faces being inclined transversely at an angle 100 of substantially twenty degrees to the horizontal and inclined upwardly longitudinally toward each other.

5. A rail section for switches and frogs 105 including a body portion having a base flange, web and head, the web being thickened to provide cam wheel engaging faces forming continuations of each other, said faces being inclined transversely at an angle 110 to the horizontal and inclined longitudinally toward each other.

In testimony whereof I affix my signature in presence of two witnesses.

DANIEL R. ALLEN. [L.S.]
